CLAIM

The ornamental design for an ice scoop, as shown and described.

DESCRIPTION

FIG. 1 is a top front perspective view of an ice scoop of the present disclosure;

FIG. 2 is a rear perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof;

FIG. 9 is a partially enlarged view thereof, taken from FIG. 1;

FIG. 10 is a partially enlarged view thereof, taken from FIG. 8; and,

FIG. 11 is a partially enlarged view thereof from FIG. 8. The dot-dash broken lines of FIGS. 1 and 8-11 are included to show the partially enlarged views only and form no part of the claimed design.

1 Claim, 11 Drawing Sheets
